UNITED STATES PATENT OFFICE.

THOMAS E. McCORMICK, OF CANTON, OHIO.

RAILROAD-TIE.

972,890.

Specification of Letters Patent. Patented Oct. 18, 1910.

Application filed December 26, 1908. Serial No. 469,429.

To all whom it may concern:

Be it known that I, THOMAS E. McCORMICK, a citizen of the United States, and resident of Canton, in the county of Stark 5 and State of Ohio, have invented certain new and useful Improvements in Railroad-Ties, of which the following is a specification.

My invention relates to railroad ties, and 10 particularly to metallic ties, and comprehends the utilization of a hollow reinforced construction and an elastic rail-bearing surface detachably fitted within the frame.

My invention further comprehends the 15 tapering of the tie in such manner that the supporting portion shall be of greater area than the rail-carrying portion and that the bearing portion shall carry its greatest width between the rails and taper to the 20 outer end of the tie.

It also comprehends the location of a recess in the end of the tie whereby the 25 elastic rail-bearing member may be embedded in the frame and a recess for the adjustment of the means that hold the elastic rail-bearing member and the rail clip.

Heretofore in hollow metallic railroad ties it has been the custom to manufacture the 30 same in hollow pipe form of somewhat square shape in cross section and in some instances to place metallic reinforcing within the same or to fill the same with cement and in railroad ties formed from a casting there has been no idea of hollow pipe casting 35 but what might be termed a simple frame casting. Both of these forms of tie had distinct advantages yet neither of them could be termed a practical railroad tie and realizing the faults of both of these constructions I have devised a tie which in my 40 opinion obviates all these difficulties at the same time producing from a casting a hollow frame tie that is of sufficient bulk to maintain its position and to so construct it 45 that it cannot be dislodged without great difficulty when it is once placed in position.

To explain my idea Figure 1 represents a drawing of the side view of the railroad tie embodying my invention, showing part of 50 the same in section. Fig. 2 represents a plan view of the same. Fig. 3 is a vertical section on the line 3—3 Fig. 1.

From an inspection of the drawing, more 55 particularly illustrated in the section disclosed in Fig. 3, it will be observed that the central part of the tie between the rails is

cast hollow and that lateral ribs project not only on the outside but on the inside and that the walls of the casting project below the level of the casting itself, forming ribs 60 along the bottom thereof and for the purpose of reinforcing the upper portion of the casting I have arranged one cross brace having lateral ribs projecting therefrom in the same manner as the body of the casting. I 65 have done this principally to save weight. It will also be observed that the construction just described refers to the central portion of the casting or the portion between the rails and which for convenience I desire to 70 term the supporting portion.

The tie is constructed in this manner so that when the same becomes embedded in the earth the central portion acts as a wedge in the earth to form a solid foundation for 75 and to resist any strain brought upon the rails by the passing of the train.

To more fully describe the details of my invention, the tie may be divided into two parts, the central portion between the rails 80 and the rail-carrying portion. The central portion between the rails is cast hollow, the side walls a and b thereof projecting below the body of the casting and forming the vertical projections for preventing the tie from 85 moving when once embedded in the earth. These side walls are also provided exteriorly and interiorly with lateral flanges a' a'' , b' b'' , the function of which is the same as the lower projection of the side walls. A vertical brace c is provided, extending along the upper portion of the ties, which latter also carries lateral flanges c' c'' . From an inspection of a sectional view of this construction it will be perceived that when the tie is 90 embedded in the earth, the space on the interior and exterior will be filled with earth, practically making it impossible to move the tie when once set in position; and to further provide that the earth may thoroughly fill 95 the interior of the tie, I have provided slots a^3 and b^3 in the side walls. It is my intention to construct these flanges with the exception of the top brace, so that they shall be widest or project farthest between the 100 rails and gradually taper them to the outside end of the tie.

The end portions d of the tie are preferably cast with two recesses e and h , the recess e being parallel with the direction of 110 the rail and so arranged that an elastic substance e' , such as wood, may be inserted

therein for carrying the rail; and the other recess, h , being at right angles thereto and so arranged that the bolt g of the rail-securing means f shall project therein so that a nut attached thereto may be adjusted to hold the rail in position.

It will be observed from an inspection of Fig. 1, that the hollow central portion and the rail-carrying portion are separated by a 10 dam or brace d' d^2 , the upper portion d' being inclined from bottom to top to form a brace for the lateral flanges c' c^2 of the vertical brace c and also to save weight in the casting.

15 I have tapered the tie from the bottom to the top and also from a suitable point between the rails to the end of the tie, and I have provided the vertical brace c in the center of the tie so that should it be desirable to 20 embed the tie in cement for the purpose of street railroads a very small portion of the same would appear above the surface and in this utilization of my tie it would be my intention to countersink the rail so that the top 25 of the same would practically coincide with the upper surface of the tie and also to provide an arm hole at the end of each tie so that access can be had to the rail-securing means within the recess below the rail.

30 It will be apparent from an inspection of the drawing that when a tie manufactured in accordance with my invention is placed in the earth and the earth suitably tamped or packed around and within it, the lateral 35 flanges and the vertical flange at the bottom together with the resistance afforded by the vertical top brace with its lateral flanges render the tie absolutely immovable and that by a removal of a slight amount of earth at 40 the ends of the tie, the elastic rail-bearing means may be removed and renewed and the life of the tie only limited by the capability of the material of which it is composed for resisting the action of the atmosphere.

45 Having described my invention what I claim and desire to secure by Letters Patent is:

1. A railroad tie having, in combination, a central slotted anchoring portion com-

posed of a plurality of flanged bars and a 50 rail-bearing portion arranged in extension thereof at each end, said bearing portions each having a transverse groove remote from the slotted portion, and an elastic material set in said groove. 55

2. A railroad tie having, in combination, a central slotted portion composed of a plurality of separated bars having laterally extending flanges, and a top portion provided with a transverse groove in each end, and 60 rail-bearing material of a substance different from the tie secured in said groove.

3. A railroad tie comprising a central slotted body the sides of which converge toward its top, and the bars of which are 65 flanged to provide anchoring portions and a rail-bearing portion at each end of the slotted portion provided with a transverse groove, and an elastic rail-bearing material secured in said groove. 70

4. A railroad tie having a central body portion and rail-bearing end portions, each of the latter being provided with a transverse groove in its surface, and a longitudinal chamber extending from the end 75 thereof toward the anchoring portion and extending under said groove, a rail-bearing block set in said transverse groove with its surface flush with the surface of the central portion, and rail-fastening means carried by 80 said block including bolts passing through the latter into said chamber.

5. A railroad tie having, in combination, a central portion tapered from its bottom to its top and end portions each tapered on 85 its opposite sides and on its bottom from the central portion to its end, and a rail-bearing block carried by said end portion having its surface flush with the surface of the central portion. 90

Signed at Canton in the county of Stark and State of Ohio this 12th day of December, A. D. 1908.

THOMAS E. McCORMICK.
